Manufacturing Company, Chicago, Ill., a corporation
of Illinois

Application November 13, 1956, Serial No. 621,588

5 Claims. (Cl. 262—7)

This invention relates to improvements in mining machines of the boring type, and more particularly to rotary trimmer bars used on such mining machines.

Mining machines of the type above mentioned are usually characterized by a mobile frame having a plurality of boring heads rotatable on parallel axes for cutting a plurality of contiguous bores in advance of the machine, together with horizontally extending trimmer bars disposed rearwardly of and generally tangential to adjacent pairs of boring heads, so as to trim or cut off the depending and upstanding cusps left between said boring heads. The present invention relates particularly to bit-carrying trimmer bars rotatable on horizontal axes, of the kind broadly disclosed in Patent No. 2,734,731, issued February 14, 1956.

In a co-pending application, Serial No. 619,812, filed November 1, 1956, owned by the assignee of this invention, means are disclosed for oscillating the trimmer bars in endwise direction while the machine is in operation so as to enhance the effectiveness of the cutting action, while requiring a relatively small number of cutter bits. In that application, trimmer bars are journalled in supports which are localized within the paths of movement of the boring heads so that the trimmer bars are oscillated about relatively long radii rather than being oscillated directly in line with their respective axes.

Among the objects of the present invention is to provide a variant form and arrangement of rotary trimmer bars and supporting means therefor which causes the trimmer bars to be oscillated longitudinally of their respective axes rather than in slightly arcuate paths.

A further object of the invention is to provide supporting means for the oscillating trimmer bars which permit the latter to be adjusted vertically so as to cut at different levels relative to the floor or roof of the mine.

Other objects and advantages of the invention will appear from time to time as the following description proceeds:

The invention may best be understood by reference to the accompanying drawings, in which—

Figure 1 is a front view of a mining machine constructed in accordance with the invention;

Figure 2 is an enlarged detail section taken on line 2—2 of Figure 1;

Figure 3 is a detail section taken on line 3—3 of Figure 2;

Figure 4 is a detail section taken on line 4—4 of Figure 1;

Figure 5 is a detail section taken on line 5—5 of Figure 4;

Figure 6 is a detail section taken on line 6—6 of Figure 5; and

Figure 7 is a diagram of the hydraulic circuit employed for oscillating the rotary cutter bars along their axes.

Referring to details of the embodiment of the invention illustrated in the drawings, Figure 1 shows the front end view of a mining machine having a horizontally elongated frame 10 which rotatably supports four laterally spaced

2

boring heads 11, 12, 13 and 14. In the illustrative form shown, each of the boring heads consists of single rotary arms 11a, 12a, 13a and 14a, respectively, having similar arcuate cutter bit supports 15 at their outer ends, and a cutter bit support 16 intermediate its ends. Each of said rotary arms is supported at its inner end on a drive shaft, the shaft of one of the outermost heads 14 being shown at 14b in Figure 4, and the shaft of the adjacent head 13 being shown at 13c in Figures 2 and 3. The four cutter heads are rotated as usual at equal speeds and in synchronized relation to each other, the two heads at the left side of Figure 1 being preferably rotated in counterclockwise direction, and the heads at the right side being rotated in clockwise direction, so that both pairs of heads tend to sweep the cuttings inwardly toward a center opening or throat 18 for loading on the front end of a cuttings conveyor 19, which carries the cuttings along the frame for discharge at the rear of the machine, as is common with machines of this type.

Referring now more particularly to the trimmer bars which form the subject matter of the present invention, an upper bar support 20 and a lower bar support 21 are disposed respectively along the top and bottom edges of the frame 10, immediately to the rear of the paths of movement of the boring heads. Each of said supports have similar trimmer bar sections 23 rotatably journalled along their front faces. In the form shown herein, the upper and lower bar supports each have two pairs of trimmer bar sections in longitudinal alignment with each other, and each bar section is driven from the adjacent outermost cutter head.

The lower trimmer bar support 21 extends the width of the machine between the axes of the outermost cutter heads 11 and 14, and is vertically adjustable relative to the frame 10 by a pair of piston rods 25, 25 working in hydraulic cylinders 26, 26 fixed to the front end of said frame. The upper trimmer bar support is similarly adjusted by piston rods 27 in cylinders 28. This general arrangement for providing vertical adjustment of the upper and lower trimmer bar supports is substantially the same as has been previously employed with cutter-chain carrying trimmer bars, excepting for the modifications required for mounting, driving and oscillating the rotary bar sections 23 on their supports, as will now be described. Since the four trimmer bar sections 23 and their driving and oscillating means are identical, a detailed description of the bar section 23 at the lower right-hand side of Figure 1 will suffice for the understanding of all of said sections.

Each trimmer bar section 23 consists of shaft 30 having cylindrical inner and outer cutter portions 31 and 32. The shaft 30 has a reduced intermediate portion 30' journalled in a bearing 33 and a reduced end portion 42 extending into a bearing housing 46.

Each of said cylindrical cutter portions has a spiral rib 34 on its outer surface along which cutter bit sockets 35 are formed in spaced relation for receiving cutter bits 36 which are detachably secured in said sockets by suitable means. In the form shown, all of the cutter bits 36 are disposed in the same diametrical plane along the trimmer bar.

When the cutter bits 36 are fixed in operative position, the ends of their blades 37 move in paths extending vertically above and below the trimmer support 21 so as to cut a clear path for said support as the machine is advanced.

The bearing member 33 through which the shaft 30 passes, is disposed to the rear of the boring head 13, in the lower center part of the bore pattern of the latter, so that said boring head cuts a path for said bearing member. The reduced end portion 42 of the shaft 30 is splined at 43 which has slidable engagement in splined in-

ner bore 44 of a worm 45 rotatably supported in the housing 46, fixed on the outer end of the lower bar support 21. As will also be seen in Figure 1, the housing 46 just mentioned is disposed to the rear of the boring head 14 at the point of maximum cutting diameter thereof, so that said boring head cuts a path for said housing.

The worm 45 is driven from a worm wheel 47 rotatably mounted on an upright axes in bearings 47' and 47" in the housing 46 as shown in Figure 4. In the form shown herein, the housing 46 consists of an enlarged forwardly projecting portion of the lower bar support 21, enclosed at the bottom by a detachable cover plate 48 and at opposite ends of the worm 45 by a cover plate 49 and a sealing plate 50.

The worm wheel 47 has a splined interior indicated at 51, engaged by a splined end 52 of an upright shaft 53. The latter shaft has a bevel gear 54 suitably fixed at its upper end and having bearing in a housing 55 carried on the main bearing support 15b for the drive shaft 14b of the cutter head 14. A bevel gear 56 is keyed at 57 to a projecting hub portion 14c of the cutter head, which hub portion is keyed at 58 to the drive shaft 14b. The arrangement just described is such that the upright shaft 53, connected to the worm gear 47 and the worm 45, will be driven from the main drive shaft 14b of the cutter head 14 and in turn will rotate the two trimmer bar sections 31 and 32. The teeth on the worm have a sufficiently steep pitch to permit the worm to be driven from the worm wheel.

The trimmer bar section 23 is arranged for endwise oscillation relative to the cutter bar support 21. As seen in Figures 2 and 3, the bearing member 33 which supports the connecting shaft 39' between the cylindrical sections 31 and 32, is slidably mounted relative to the lower supporting bar 21 by a rearwardly projecting arm 60 having a socket 61 on its inner end engaged by a ball 62 on the lower end of a rod 63. The arm 60 connecting the bearing member 33 to the ball and socket joint 61, 62 is held in place on the supporting bar 21 by a plate 66 extending over the arm 60 and detachably connected at opposite ends to the supporting bar as seen in Figures 2 and 3. The rod 63 is telescopically mounted in a cylindrical arm 64 forming a part of a rocking collar 65 pivotally mounted on the bearing support 13b of the cutter head 13.

Means are provided for oscillating both the upper and lower pairs of trimmer bars 23, 23 on their respective supports 20 and 21 by hydraulic power, as shown in greater detail in the diagram of Figure 7. As will be seen from this figure, rocking collars 65, 65 are mounted on the bearing supports 12b and 13b of the inner cutter heads 12 and 13, and are connected for simultaneous rocking movement by a link 67 pivotally connected at opposite ends to the cylindrical arms 64a corresponding to the cylindrical arms 64 on the lower part of said rocking collars. The two telescopic rods 63 on said rocking collars are connected by similar ball and socket joints to the two bearing members 33 of the lower trimmer bar sections 23, while the corresponding telescopic rods 63a extending from the top of the rocking collars 65 similarly engage the two bearing members 33 of the upper trimmer bar sections 23. The lower trimmer bar sections are oscillated along their axes in reciprocal relation to the upper trimmer bar sections by means of a pair of oppositely acting hydraulic motors 70, 71 of the cylinder and piston type (see Figure 7).

The motors 70 and 71 are actuated by hydraulic pressure supplied thereto from a pump 72 having a high pressure line 73 passing through a manual control valve 74 and thence through pressure line 75 to an automatic reversing valve 76. This reversing valve is of a conventional type well known in the art, having a rotating valve element 77 adapted to be thrown in one direction or the other by a forked control lever having a pair

of spaced contact members 78 and 79 so as to direct the flow of fluid from the pressure line 75 to a return line 80 either through lines 81 or 82 which lead to opposite sides of the motors 70 and 71. The arrangement is such that when pressure from line 75 is introduced in the line 81, it will be conducted through line 81a to the upper end of the cylinder of motor 70, thus moving the piston 70a of said motor downwardly to rock the arm 65a of sleeve 65 in a counterclockwise direction. A second branch 81b of the line 81 is connected to the lower end of the motor 71 so that when pressure is introduced in said line, the piston 71a of motor 71 will rock the arm 65a of the other rocking sleeve 65 in a counterclockwise direction. While pressure is being fed through line 81 and branch lines 81a and 81b to the upper and lower ends of motors 70 and 71, pressure will be relieved respectively from the lower and upper ends of said motors to branch lines 82a and 82b connected respectively to the lower and upper ends of the motors 70 and 71 and thence through line 82 and valve 76 to the return line 80 leading to the supply tank 84. This rocking movement will continue until a contact finger 83 on one of the rocking arms 65a will engage the contact member 79 of fluid switch 76, whereupon the switch will be thrown into a second position to reverse the flow of fluid to the motors 70 and 71 and cause the rocking sleeves 65 to rock in a clockwise direction until the contact finger 83 again reverses the direction of flow by engagement with the contact arm 78.

Although I have shown and described a certain embodiment of my invention, it will be understood that the invention is not limited to the exact construction shown and described herein, but that various changes and modifications may be made without departing from the spirit and scope of the invention as defined in the appended claims.

I claim:

1. In a mining machine of the boring type having a mobile frame with a plurality of boring heads journaled on parallel axes for cutting a plurality of contiguous bores in advance of the machine, a horizontally extending trimmer bar disposed generally tangential to but rearwardly of an adjacent pair of boring heads to cut off the cusp left between said adjacent boring heads, said trimmer bar including an elongated supporting bar, a rotary cutter-carrying bar along the front of said supporting bar to cut a path in front of the latter, means for rotating said cutter bar on its axis, and means including a pair of laterally spaced telescopically extensible arms rockably mounted on said frame for oscillating said cutter bar in said supporting bar axially of said cutter bar, and in a substantially fixed vertical plane.

2. The structure of claim 1 wherein the means for rotating the cutter bar on the supporting bar includes power connections from the frame independent of the oscillating means.

3. The structure of claim 1 wherein the supporting bar is adjustable vertically relative to the frame, and the means for rotating the cutter bar on the supporting bar include telescopically extensible power connections from the frame.

4. The structure of claim 3, wherein the power connection for rotating the cutter bar comprises a drive gear on the frame, a gear train on said supporting bar including a gear on an upright axis driving a gear on the axis of the cutter bar, an extensible drive shaft connection between the drive gear on the frame and the first named gear on the supporting bar, and another extensible drive connection between the second named gear on the supporting bar and the cutter bar.

5. The structure of claim 3, wherein the extensible arms for oscillating the cutter bar are fulcrumed on the frame for parallel rocking movement to and from opposite sides of vertical planes including the axes of two

2,825,545

5

of the boring heads, and the ends of the extensible arms
are pivotally connected to the supporting bar.
